CONTROL PANEL FOR A COMBINED RADIO AND PHONOGRAPHS OR SIMILAR ARTICLE

Herbert J. Zeller, Dundee, Ill., assignor to Motorola, Inc.,
Franklin Park, Ill., a corporation of Illinois

Design application Sept. 28, 1967, Ser. No. 9,703, which
is a division of application Ser. No. 87,970, dated Nov.
1, 1965, now Patent No. 210,100, dated Feb. 6, 1968.
Divided and this application Apr. 11, 1968, Ser. No.
11,410

Term of patent 14 years

(Cl. D56—4)

FIG. 1 is a front elevational view of a control panel for a combined radio and phonograph or similar article showing my new design;

FIG. 2 is a right side elevational view;

FIG. 3 is a left side elevational view; and

FIG. 4 is a top plan view thereof.

The broken line showing a portion of a combined radio and phonograph in which the control panel may be mounted is for illustrative purposes only.

This is a divisional application of my co-pending application D. 9,703 which was filed on Sept. 28, 1967 and which in turn is a divisional application of D. 87,970 which was filed on Nov. 1, 1965 and is now D. 210,100 issued on Feb. 6, 1968.

I claim:

The ornamental design for a control panel for a combined radio and phonograph or similar article, as shown and described.
